New York, N. Y., a corporation of Delaware

Application October 19, 1943, Serial No. 506,803

11 Claims.

(Cl. 179—15)

This invention relates to multiplex communication systems and more particularly to communication systems using time modulated pulses to convey the wanted intelligence.

It has been proposed to transmit intelligence by a series of pulses, modulated in time in accordance with the desired message. A multiplex system of this type is shown in the patent to E. M. Deloraine and A. H. Reeves, No. 2,262,838. In the patent, however, the synchronizing system for assuring properly timed operation of the transmitters and receivers is only generally indicated. Furthermore, no intermediate or branch terminals are provided, and two-way simultaneous transmission on the same line is not contemplated.

It is an object of my invention to provide a multi-channel communication system with a novel method of synchronization and power supply.

It is a further object of my invention to provide a system for two-way pulse communication on a single transmission medium.

It is a still further object of my invention to provide a multi-channel pulse communication system wherein one or more of the channels may be terminated at an intermediate or branch circuit.

It is a still further object of my invention to provide means for supplying power to an intermediate repeater station from one terminal of a pulse communication system.

With these objects and others in view the system according to my invention may include a pair of terminal stations interconnected by a common line. At an intermediate point in the line may be provided an intermediate or branch terminal which may be arranged to communicate with either or both the regular terminals over one or more channels. A power source at one terminal may furnish power at the intermediate terminal and to line repeaters in the line. At the same time the energy from the power source may serve to synchronize operation of the transmitter and receiver equipment at the intermediate terminal and the other terminal of the system. In order to communicate simultaneously in both directions over the common line the signals may be carried in one direction by simple modulation of pulses, preferably in time, and in the other direction by a carrier frequency wave modulated by the modulated pulses.

Other objects and features of my invention will become more apparent from the particular

description of an embodiment thereof made with reference to the accompanying drawings, in which:

Figs. 1, 2 and 3, taken together, illustrate schematically a complete multi-channel pulse communication system, with one terminal in Fig. 1, a branch circuit repeater or terminal in Fig. 2 and the other terminal in Fig. 3.

Turning to the drawings, in Fig. 1 is illustrated terminal equipment 10 coupled over line 11 and through a repeater 12 to the intermediate or branch terminal equipment 13, shown in Fig. 2. The intermediate branch terminal 13 is coupled over line 11 and a repeater 14 to the other terminal equipment 15, Fig. 3.

At terminal 10 are shown in full lines three terminal connectors 1, 2 and 3 which may be coupled to two-way transmission voice lines over a selector switch, if desired. Additional channels may be provided, as indicated by the dotted rectangles. Lines 1, 2 and 3 are coupled over hybrid coils 101, 102, 103, each provided with balancing networks 104, 105, and 106, respectively, to transmitting and receiving equipment preferably of the time modulated pulse type. On the transmitting side hybrid coils 101, 102 and 103 are coupled to the input modulators 107, 108 and 109, respectively, the outputs of these modulators being applied over band pass separating filter 113 adjusted to pass the impulse frequencies, and high pass filter 114 to line 11. These modulators are separately controlled in a known manner, by means of energy applied over line 140 from a synchronizing source 112 and the respective phase shifters 117, 118, and 119, so as to apply signals to filter 113 in spaced sequence.

At 110 is provided an alternating current power source which should be well regulated to maintain a constant frequency. The frequency of the alternating current from this power source is preferably a submultiple frequency of the cadence frequency of the impulses transmitted from modulators 107, etc. For example, if the cadence frequency of the impulses is 12 kilocycles, the power source may be 3000 cycles. It is clear that lower or higher frequencies for the power source may be provided, if desired. Energy from power source 110 is used to control synchronizing source 112 to produce the desired control frequency for switching the modulators. A rectifier 111 is also coupled to the output of power source 110 and over line 150 is used to supply the operating power for the modulators 107, 108 and 109 as well as for the demodulators 127, 128 and 129 and the group detector 135, to be described later. Power

from source 110 is also applied over low pass filter 115 to line 11 serving to supply the low frequency power for unattended repeaters, such as 12 and the intermediate channel repeater 13, shown in Fig. 2.

Line 11, as shown, serves as a two-way communication line, the incoming signals to terminal 10 being supplied by way of a carrier frequency sufficiently high to carry the signal bearing pulses. The incoming signal energy from line 11 passes over high pass filter 114 and band pass separating filter 133, adjusted to pass the modulated carrier frequency to group detector 135. Group detector 135 serves to detect the impulses incoming over line 11 and removes the carrier frequency therefrom. The output signals from group detector 135 are applied to demodulators 127, 128 and 129 which demodulators are then coupled to the input side of hybrid coils 101, 102 and 103 and hence to line terminals 1, 2 and 3. The proper timing of the demodulators for separating the incoming channels is achieved by energy from synchronizing source 112. This synchronizing energy is passed over a phase shifter 116 and line 155 serving to compensate for the transmission time of line 11 and over individual phase shifters 137, 138 and 139, which serve to segregate the various channels, to demodulators 127, 128 and 129, respectively.

In Fig. 2 is shown an intermediate or branch terminal repeater serving to select one or more of the channels incoming over line 11 from both directions. To line 11 are coupled high pass filter 214 and low pass filter 215 serving to separate the signal frequencies and the low frequency power energy from line 11. Band pass filters 213 and 233, coupled over high pass filter 214 serve to separate out energy from terminal 10 and from terminal 15 respectively. Energy from the output of low pass filter 215 is applied to the rectifier 211 which, in turn, supplies operating power to demodulator 207, modulator 227, demodulator 228, modulator 208, synchronizing oscillator 212, and to other modulators and demodulators, as required over lines 270, etc. At the same time, energy from the output of low pass filter 215 serves to synchronize the operation of synchronizing control oscillator 212 which serves to switch into operation the modulators and demodulators in proper sequential order to select the desired transmission channel and to assure application of energy from the modulator to line 11 in proper timed relation for reception at either of the terminals 10 or 15 over lines 260, 261, 262 and 263.

In order more clearly to explain the operation of my invention as applied to the drop channel, we may best trace through the transmission of a channel between terminal 10 and intermediate terminal 13. For this purpose, it may be assumed that channel 1 associated with hybrid coil 101 is being terminated at the branch station. Under these circumstances, signal energy from 101 is applied to modulator 107 and over filters 113 and 114 to line 11. Upon reaching branch terminal 13, energy from synchronizing oscillator 212 is supplied over phase shifter 217 to demodulator 207 so that demodulator 207 will be operated in proper timed relation to select channel 1. Energy from this channel is applied to demodulator 207 over band pass filter 213, and the incoming pulses are thus demodulated. The demodulated pulses may carry with them ringing or other signaling energy as well as voice frequency energy. The output of demodulator 207 is coupled to low pass filter 240 and if ringing signal is present

ringing relay 244 is operated, intermittently closing contacts 245, and applying ringing signals to outgoing voice line 246. When ringing signals are not present, the demodulated voice signals are passed over high pass filter 241 to the input side or hybrid coil 242 and hence to line 246.

Incoming voice signals over line 246 are applied to hybrid coil 242 which is provided with balancing network 243 and from hence to pulse modulator 221. Pulse modulator 221 is controlled by phase shifter 237 also in turn controlled by energy from synchronizing oscillator 212. Phase shifter 237 is adjusted properly to time the pulses of this channel to fit into the return trains of channels for suitable selection at terminal 10. These pulses from the output of modulator 221 are applied to carrier modulator 235 which serves to provide the carrier frequency for communication to terminal 10. The output from carrier modulator 235 is then applied over band pass filter 233 to line 11 and hence back over repeater 12 to terminal 10. This carrier energy is then passed over high pass filter 114 and selected by band pass filter 133 for application to group detector 135 along with the other incoming signal impulses from line 11. The proper signals for channel 1 are selected in demodulator 127 by means of the control wave applied over phase shifter 137 and from hence to the input side of hybrid coil 101 and from there to line terminal 1.

It can thus be seen that with this arrangement, communication may be established between terminal 10 and intermediate or branch terminal 13. Should it be desired to select a different channel for demodulation at 207 and modulation at 221, phase shifters 217 and 237 may be adjusted by means of a common control 201 to provide application of the control wave in proper timed relation to select the desired channel. To this end phase shifters 217 and 237 are preferably made to operate in steps so that each step constitutes substantially the normal time displacement between pulse signal channels. Alternatively, the switching may be made at terminals 1, 2 and 3, so that the desired voice line may be connected to a permanent trunking channel for branch terminal 13. The signals selected at the branch terminal also traverse the line to the other terminals but if desired the equipment there may be disabled under control of an operator.

The signals from terminal 10 after passing intermediate or branch terminal 13, may pass over a further repeater 14 and over line 11 to terminal 15. Here are provided the high pass and low pass filters 314 and 315 which serve to separate the power energy from the incoming pulse signals. The power energy may operate through a synchronizer 334 synchronously to control a local power source 310. It is clear that, if desired, the operating power could be derived directly from the incoming power signals but it is preferable to provide the local power source 310.

The output of local power source 310 may be applied directly to the demodulators 307, 308, 309 and modulators 321, 328 and 329 and to group modulator 335. At the same time the synchronizing signals from synchronizer 334 may be applied to synchronizing source 312 which serves to control the switching into operation of the demodulators and modulators in proper timed relation over phase shifters 317, 318, 319, 337, 338 and 339, respectively.

On the modulating side or transmitting side of terminal 15, an additional phase shifter 336 is provided to take care of the difference in trans-

mission time between the modulator and demodulator groups. The various channels from terminal 10 are thus selected at terminal 15 and applied over hybrid coils 301, 302 and 303 provided with balancing networks 304, 305 and 306, respectively, to the separate voice frequency lines.

In order clearly to explain the operation of this system, the transmission of signals from 15 toward 10 will be traced. We may assume now that the channel incoming over 302 is the one to be traced. The incoming signal energy from 302 is applied to modulator 328, the output of this modulator is then applied to group modulator 335 along with the signals from the other modulators. Modulator 335 serves to modulate a suitable carrier frequency with these pulses to separate these outgoing channels from the incoming modulated pulse signal channels. These signals from modulator 335 are then applied over band pass filter 333 and high pass filter 314 to line 11. The signals incoming over line 11 to the branch repeater 13 are applied to carrier detector 257 over band pass filter 233 and hence to demodulator 228 controlled by phase shifter 238. If phase shifter 238 is adjusted properly to select this channel, the energy is demodulated therein. The ringing signal is segregated by low pass filter 250 serving to operate ringing relay 254 and ringing contacts 255 to apply to lines 256 these ringing signals. Voice signals are applied over high pass filter 251 and hybrid coil 252 to the voice line 256.

In the return transmission from terminal 13 to terminal 15 voice signals incoming over line 256 are applied to hybrid coil 252 which is also provided with balancing network 253 to modulator 208. Modulator 208 is controlled by phase shifter 218 to produce the proper time spacing for the incoming pulse channel. The modulated impulses are then applied over band pass filter 213 to line 11 and over repeater 14 to terminal 15. The incoming signals to terminal 15 pass over high pass filter 314, band pass filter 313 to demodulator 308 and from there to the input side of hybrid coil 302.

Assuming the channel is not selected for dropping at intermediate terminal 13, the impulses pass over line 11 and repeater 12 to terminal 10. Here the incoming signals pass over high pass filter 114 and band pass filter 133 to group detector 135 where the pulses are reproduced. These reproduced pulses are then applied to demodulator 128 and from there the demodulated signal is applied to hybrid coil 102 in line 2.

It should be understood that repeaters 12 and 14 must be arranged suitably to pass not only the impulse energy and the carrier frequency but also the energy from power source 110. Accordingly, these repeaters cannot readily be made as simple pulse repeaters but instead may be straight linear repeaters. In any case it may be desirable to bypass the power energy about repeaters 12 and 14 by means of low pass filters 22 and 23, respectively.

However, it should be understood that at the same time some of this energy may be tapped off by rectifier arrangements similar to those shown at the branch terminal repeater for energizing the tubes within the repeaters. Thus, the system, as described, is admirably suited to the operation of unattended repeater stations where localizer power supply is difficult to obtain.

Likewise, it is clear that, if desired, separate transmission lines between terminals 10 and 15 may be used for opposite directions instead of

using the carrier energy for the two way repeater operation.

It is also clear from the description given above that the power source 110 serves the double purpose of supplying power at the repeater stations and of synchronizing operation of the terminal equipment at the branch terminals and at the far terminals of the system.

It should likewise be distinctly understood that any suitable type of modulator and demodulator equipment may be used in place of that illustrated and described. While I have disclosed a specific form of my invention it should be clearly understood that this is offered merely as an example and not as a limitation on the claims of the invention. The specific example, therefore, should not be considered as a limitation on my invention as expressed in the objects thereof and in the accompanying claims.

20 What is claimed is:

1. A multi-channel communication system comprising a first terminal, a second terminal, a common transmission line interconnecting said terminals, means at said first terminal for producing a plurality of trains of impulses each representing a communication channel, an alternating power source for supplying energy at said first terminal, means at said first terminal for producing from energy of said source a control wave for timing the impulses of each channel to interspace said impulses in time spaced relation on said common transmission line, means for applying power energy from said power source to said line, a branch terminal having receiving means coupled to said common transmission line between said first and second terminals, and means at said branch terminal responsive to said power energy for energizing said receiving means, and selector means responsive to said power energy for timing operation of said receiving means, to select a predetermined channel at said branch terminal.

2. A multiplex signaling system comprising first and second terminals with a two-way transmission system therebetween, each of said terminals having a plurality of stations, each station having a transmitting circuit and a receiving circuit, each transmitting circuit having means for generation of a train of time modulated pulses representing one channel of communication, control means at said first terminal to control the timing of the transmission of pulses from stations thereof to sandwich the pulses together with a given timing characteristic between successive pulses of the resulting train of channel pulses, means for applying said resultant train of channel pulses and energy from said control means to said transmission system for transmission to said second terminal, means at said second terminal responsive to energy from said control means to control the alignment of the receiving circuits thereof with the proper channel pulses from said first terminal, and further to control the timing of the transmitting circuits of said second terminal for channel communication back to said first terminal, a branch terminal having one or more stations each having a transmitting circuit and a receiving circuit, a line junction connecting said branch terminal to said two-way transmission system, and means for placing any one of said channels of communication in service between any station of said first and second terminals and a station of said branch terminal.

3. The system defined in claim 2 wherein the

means for placing any one of said channels of

communication in service between any station of said first and second terminals and a station of said branch terminal.

4. The system defined in claim 2 wherein the

means for placing any one of said channels of

communication in service between any station of said first and second terminals and a station of said branch terminal.

5. The system defined in claim 2 wherein the

means for placing any one of said channels of

communication in service between any station of said first and second terminals and a station of said branch terminal includes means for determining at the branch terminal the pulse timing of any given channel, and means responsive to energy from said control means to time the transmitting and receiving circuits of a branch station in accordance with the timing of said given channel.

4. A multiplex signaling system comprising first and second terminals with a two-way transmission system therebetween, each of said terminals having a plurality of stations, each station having a transmitting circuit and a receiving circuit, each transmitting circuit having means for generation of a train of time modulated pulses representing one channel of communication, a power source of alternating current waves at the first terminal, control means at said first terminal timed by said alternating current waves to control the timing of the transmission of pulses from stations thereof to sandwich the pulses together with a given timing characteristic between successive pulses of the resulting train of channel pulses, means for transmitting alternating current waves from said source to said second terminal, means at said second terminal responsive to alternating current waves to control the alignment of the receiving circuits thereof with the proper channel pulses from said first terminal, and further to control the timing of the transmitting circuits of said second terminal for channel communication back to said first terminal, a branch terminal having one or more stations each having a transmitting circuit and a receiving circuit, a line junction connecting said branch terminal to said two-way transmission system, means for deriving energy from said alternating current waves to energize said transmitting and receiving circuits, means responsive to said alternating current waves for timing operation of said transmitting and receiving circuits, and means for placing one of said channels of communication in service between any station of said first and second terminals and a station of said branch terminal.

5. A multiplex signaling system comprising first and second terminals with a transmission line therebetween, a plurality of stations at said first terminal, each station having a transmitting circuit, each transmitting circuit having means for generation of a train of time modulated pulses representing one channel of communication, a power source of alternating current waves at the first terminal for energizing said transmitting circuits, control means at said first terminal timed by said alternating current waves to control the timing of the transmission of pulses from stations thereof to sandwich the pulses together with a given timing characteristic between successive pulses of the resulting train of channel pulses, means for applying said pulses and energy from said source to said transmission line, means at said second terminal responsive to alternating current waves to control the alignment of the receiving circuits thereof with the proper channel pulses from said first terminal, a branch terminal having one or more stations each having a transmitting circuit and a receiving circuit, a line junction connecting said branch terminal to said transmission line, means for deriving energy from said alternating current waves to energize said transmitting and receiving circuits, means responsive to said alternating current waves for timing operations of said transmitting and re-

ceiving circuits, and means for placing one of said channels of communication in service between any station of said first terminal and a station of said branch terminal.

6. A multiplex signaling system comprising first and second terminals with a transmission line therebetween, a plurality of stations at said first terminal, each station having a transmitting circuit, each transmitting circuit having means for generation of a train of time modulated pulses representing one channel of communication for energizing said transmitting circuit, control means at said first terminal including a source of energy to control the timing of the transmission of pulses from stations thereof to sandwich the pulses together with a given timing characteristic between successive pulses of the resulting train of channel pulses, means for applying said pulses and energy from said source to said transmission line, means at said second terminal responsive to energy from said control means to control the alignment of the receiving circuits thereof with the proper channel pulses from said first terminal, a repeater in said line between said first and second terminals, and means at said repeater for deriving power for its operation from said energy applied to said line.

7. A multiplex signaling system comprising first and second terminals with a two-way transmission system therebetween, each of said terminals having a plurality of stations, each station having a transmitting circuit and a receiving circuit, each transmitting circuit having means for generation of a train of time modulated pulses representing one channel of communication, a power source of alternating current waves at the first terminal, control means at said first terminal timed by said alternating current waves to control the timing of the transmission of pulses from stations thereof to sandwich the pulses together with a given timing characteristic between successive pulses of the resulting train of channel pulses, means for transmitting alternating current waves from said source to said second terminal, and means at said second terminal responsive to alternating current waves to control the alignment of the receiving circuits thereof with the proper channel pulses from said first terminal, and further to control the timing of the transmitting circuits of said second terminal for channel communication back to said first terminal.

8. In a multi-channel communication system wherein a plurality of timed pulse trains each representing a separate channel and a power wave are transmitted from a given terminal station over a common medium; a second terminal coupled to said common medium means at said second terminal responsive to said power wave for energizing the circuits at said second terminal, and selector means timed under control of said power wave for selecting a pulse train representing a predetermined channel from said common medium at said second terminal.

9. In a multiplex signaling system wherein energy from a first terminal comprising a multiple timed pulse transmitting circuit and a control wave source is transmitted over a common medium, a second terminal coupled to said common medium comprising means for receiving said pulses and said control wave, means responsive to said control wave for selectively segregating the pulses representing different received channels, a multiplex transmitter means, means for transmitting a plurality of pulse channels from said

transmitter means and means responsive to said received control wave for timing the transmission of said pulses from said transmitter.

10. In a multi-channel communication system wherein a plurality of timed pulse trains each representing a separate channel and a power wave are transmitted from a given terminal station over a common medium; a second terminal coupled to said common medium, means at said second terminal responsive to said power wave for energizing the circuits at said second terminal, and selector means timed under control of said power wave for selecting a pulse train representing a predetermined channel from said common medium at said second terminal, and means for adjusting said selector means to alter the selection of channels.

11. In a multiplex signaling system wherein

5 energy from a first terminal comprising a multiple timed pulse transmitting circuit and an alternating current power wave source is transmitted over a common medium, a second terminal coupled to said common medium comprising means for receiving said pulses and said power wave, means at said second terminal responsive to said power wave for energizing the circuits at said second terminal, means synchronized in response to said power wave for selectively segregating the pulses representing different received channels, a multiplex transmitter means at said second terminal, means for transmitting a plurality of pulse channels from said transmitter means and means responsive to said received power wave for timing the transmission of said pulses from said transmitter.

EDMOND M. DELORAIN.
